UNITED STATES PATENT OFFICE.

WILLIAM HESTER, OF ROUND ROCK, TEXAS.

SEEDER AND CULTIVATOR.

SPECIFICATION forming part of Letters Patent No. 540,663, dated June 11, 1895.

Application filed April 28, 1894. Serial No. 509,324. (No model.)

To all whom it may concern:

Be it known that I, WILLIAM HESTER, a citizen of the United States, residing at Round Rock, in the county of Williamson and State of Texas, have invented a new and useful Plow Attachment for Seed-Planters, of which the following is a specification.

My invention relates to an arrangement whereby the usual corn and cotton planters are supplied with a preceding or furrow-opening plow, and it consists in certain novel features of construction and combination and arrangement of parts that will be more fully described hereinafter and finally embodied in the claim.

In the drawings, Figure 1 represents a perspective view of my complete machine; Fig. 2, a vertical section; Fig. 3, a horizontal section; Fig. 4, a detail perspective of the foot or plow-beam proper.

The reference numeral 1, indicates the frame of the planter, which may be of any kind, and which will not be further described. Secured to the front portion of the frame 1, and on either side thereof are the beams 2, which are one for each side of the frame and which are held in place by the bolts 3, passing into the frame.

From the frame 1, the beams 2 extend forwardly and inwardly and come to a juncture at a point a distance forward of the frame equal to about the length thereof. Here the beams are enlarged vertically and provided with the series of vertically aligned openings 4, whereby the draft clevis may be attached to the machine.

5 indicates a central and third beam, which is arranged between the beams 2, and is secured to the front beam by means of the tongue 6, arranged on the upper side thereof and provided with a bolt 7 passing vertically into the said front beam.

From the front beam of the frame the beam 5 extends longitudinally and forwardly and to a point even with the ends of the beams 2, to which beams the beam 5 is secured by means of a bolt 8 passing horizontally through the three. Arranged in the rear portions of the beams 2 and 5, and just forward of the frame 1, is the tie rod 9, which passes horizontally through each beam and is secured in place by the nut and head, as will be seen.

The foot or plow standard is designated by the numeral 10, and consists of a bar curving slightly forwardly and having the plow 55 blade 11 secured to its lower end. The upper end of the standard 10 is bifurcated and the arms of such bifurcations are adapted to embrace the sides of the beam 5, lying one on each side thereof, and held in place by the 60 bolt 12. Formed in the arms of the said bifurcated end are the openings or bolt holes 13, which are vertically aligned and through which the bolt 12 is adapted to pass. By means of these openings the vertical position of standard 10 may be adjusted to suit the conditions under which the machine operates. Rigidly secured to the standard 10, about midway its length is the brace 14, which extends rearwardly and upwardly and meets 70 the beam 5 at a point directly forward of the frame 1. Here the brace 14 is bent or turned to extend truly vertically, and is bifurcated so as to embrace the beam 5. 15 indicates a bolt which is passed through the arms of the 75 aforesaid bifurcation and through the beam 5 and whereby the parts are held in place.

The arms of the bifurcation in the brace 14 are provided with graduated bolt holes 16, which will permit adjusting the brace in unison with the adjustments of the standard 10.

The operation of my invention will be understood. Upon the progressive movement of the machine the plow blade 11 will operate to open the furrow, whereupon the planting mechanism will operate to drop the seed therein.

Having described my invention, what I claim is—

In a planter, the combination with a frame 90 provided with seed holding and conveying devices and furrow closing shovels, of twin forwardly convergent braces 2 secured at their rear ends to the sides of the frame and terminating in contact at their front ends in vertical enlargements provided with transversely aligned perforations, a central bar bolted at its rear end to the center of the front end of the frame and inserted at its front end in the angle between the inner or facing surfaces 95 of said braces, a bolt extending through said braces and central bar adjacent to the meeting point thereof, a transverse brace rod connecting said braces and central bar near their

rear ends, and a standard for a furrow opening shovel secured to and carried by the central bar, said perforations in the enlargements at the front ends of the braces being designed 5 for engagement by a clevis, substantially as specified.

In testimony that I claim the foregoing as

my own I have hereto affixed my signature in the presence of two witnesses.

WILLIAM HESTER.

Witnesses:
